UNITED STATES PATENT OFFICE.

WILLIAM HUCKS, JR., OF CAMDEN TOWN, LONDON, ENGLAND.

APPARATUS FOR USE IN DISPENSING AERATED LIQUIDS.

SPECIFICATION forming part of Letters Patent No. 709,407, dated September 16, 1902.

Application filed April 29, 1902. Serial No. 105,212. (No model.)

To all whom it may concern:

Be it known that I, WILLIAM HUCKS, Jr., engineer, a subject of the King of Great Britain and Ireland, residing at 22 Oval road, Camden Town, in the county of London, England, have invented certain new and useful Improvements in Apparatus for Use in Dispensing Aerated Liquids; and I do hereby declare the following to be a full, clear, and exact description of the invention, such as will enable others skilled in the art to which it appertains to make and use the same.

My invention relates to apparatus for use in dispensing aerated liquids wherein the aerated liquid is drawn from the container thereof into a closed intermediate receptacle prior to being poured into a glass for consumption; and the object of my said invention is to provide improved means by which the operation of drawing off aerated liquid into the intermediate receptacle can be performed in a more satisfactory manner than hitherto and so that in the event of the said receptacle bursting the attendant is protected from fragments thereof and from liquid, while any overflow of liquid can be conducted away without wetting the attendant or the surroundings or be returned to the said receptacle. The arrangements at the outlet from the container of the aerated liquid to be dispensed as regards the means for closing the intermediate receptacle and opening the draw-off charging-valve may consist of a valve adapted to be opened to permit the liquid to flow from the container to the intermediate vessel upon the mouth of the intermediate vessel being strongly pressed against a closing device connected with and adapted to operate the draw-off charging-valve, said valve being spring-closed upon the withdrawal of the bottle-mouth, as shown in my United States Patent No. 695,314, dated May 11, 1902. The intermediate vessel may be of any suitable kind—such, for example, as an ordinary aerated-water bottle.

The apparatus according to my invention can be conveniently used for different-sized intermediate receptacles; and a further object of my invention is to obviate expulsion of liquid from the intermediate receptacle, which is especially liable to occur if the quantity

of liquid introduced into the said receptacle nearly fills it.

In the accompanying drawings, Figure 1 is a vertical section, and Fig. 2 a front elevation, 55 of an apparatus constructed according to my invention. Fig. 3 shows in vertical section the apparatus in operation, the full lines indicating the position when a large-size intermediate receptacle is being used and the dot-and-dash lines the position when a small intermediate receptacle is being used. Figs. 4 and 5 are vertical sections illustrating modifications, and Figs. 6, 7, and 8 illustrate in different positions a further modification. 65

Referring first to Figs. 1, 2, and 3, according to my present invention to the outlet end of the pipe A, leading from the container of aerated liquid to be dispensed and carrying the draw-off valve (the stem of which is shown 70 at a) and closing device a² for the intermediate receptacle, I secure the upper end of a casing B, the lower end of which is open, the said casing being preferably of a shape or inclosing a part of a shape corresponding to 75 that of the intermediate receptacle, so that when the intermediate receptacle is introduced into the said casing from the open lower end thereof the said casing or the part inclosed in it acts as a guide to direct the 80 mouth of the intermediate receptacle to the proper position for being closed by the closing device a². In the drawings I have shown the casing B of cylindrical form, inclosing a part b to act as a guide for the aforesaid purpose. The pressure necessary to close the intermediate receptacle against the closing device a² and by continued movement to open the valve carried by the stem a is applied by a lever C, hinged to some suitable 85 part of the apparatus. In the drawings the center pin c, on which the lever C turns, is carried by bearings in the bracket-piece D secured to a counter, table, or other support D² and provided with a part at d to receive 90 the lower part of the casing B and having extensions d², through which screws d³ are passed, which screws also pass through the upper part of the casing B and into a piece A², secured to the outlet part on the pipe 100 A. The said lever C is provided with an arm C², the end of which (or a part c² swivel-

ing on the end thereof) bears upon the lower end of the intermediate receptacle and when pressure is applied to the lever forces the intermediate receptacle inward onto the closing device, so as first to close the said receptacle and then by continued movement to open the valve for charging the intermediate receptacle. This can be done whether the said receptacle be a large one or a small one, as shown in Fig. 3, where the full lines show the position of the lever C when a large bottle E is used as the intermediate receptacle and the dot-and-dash lines show the position of the lever C when a smaller bottle E² is used as the intermediate receptacle. When the required charge of aerated liquid has been drawn off into the said receptacle, the lever C is moved back, and consequently the part C², which pressed the said receptacle inward, is withdrawn and the receptacle follows it and can be withdrawn from the casing charged with aerated liquid. Any liquid which may come from the receptacle is received by the casing B, which may be provided with an outlet, as at b², to which a pipe can be secured to conduct the said liquid to any desired place.

F is a hooked lever centered at f and engaging with a pin c³ on the lever C to support it when out of use. C³ is a disk carried by the said lever C to close the end of the casing B should the receptacle E or E² be fractured during filling. To prevent liquid being forced out of the receptacle by gas when the mouth of the receptacle is removed suddenly from tight contact with the closing device a², I provide the lever C or some part connected with the casing with a device which will when the pressure of the hand of the operator is removed from the said lever prevent the mouth of the receptacle suddenly leaving the closing device and the gas escaping violently, but which will allow of the mouth of the receptacle E or E² being sufficiently relieved to permit gas to escape gently, and afterward by backward movement of the lever C the receptacle can be released from the casing B. The device may consist of a weight C⁴ on the lever C, as shown, which weight will keep the lever C in contact with the receptacle E or E² until the lever C is moved back by hand, or, as shown in Fig. 4, the part C² of the lever may be made separate from the part C, with a rod c⁴, by which the part C when depressed acts on the part C² to press on the receptacle E or E² in the casing B for closing and charging it, and when the main lever is released the part C² bears on the receptacle through the pressure of the spring c⁵ to allow of gas gently escaping, and then by backward movement of the part C the part C² is withdrawn to allow of the intermediate receptacle being withdrawn from the casing. The catch-lever F for supporting the lever C is here shown as being centered at f on the lever C and passing through a slot d⁴ in the bracket D, so as to catch against the back thereof, or the same effect can be obtained,

as shown in Fig. 5, by means of a sleeve G, attached within the casing B, through which sleeve when the receptacle is inserted into the casing B the upper part of the intermediate receptacle E passes, so as to allow of the said receptacle being filled. The mouth of the sleeve G may be eccentric to the closing device a², or a spring H may be used to press on one side of the neck of the receptacle, (or both the eccentricity and spring may be used,) so as to cause the under side of the enlargement e to be caught at one side, as shown at g, by the upper end of the sleeve G, when pressure of the lever by the operator ceases, and thus the mouth of the receptacle E does not at first leave the closing device entirely, but has first a sidewise movement upon the edge of the sleeve G, and this allows gas to escape gently. The lower end of the casing B is shown as being made large enough to admit the operator's hand, so that he can move the receptacle E from its engagement with the sleeve at g and withdraw the said receptacle from the casing B, or the arrangement may be such that liquid is allowed to be expelled from the intermediate receptacle, but is returned thereto before the receptacle is withdrawn from the casing B. This can be effected by attaching inside the casing B a flexible or collapsible sleeve I, as shown in Figs. 6, 7, and 8, through which the mouth and neck of the receptacle E pass when pressed in by the aforesaid lever C, the said sleeve engaging under the enlargement e around the neck of the said receptacle, as shown in Fig. 6. On the withdrawal of the receptacle E the sleeve I will, by the enlargement e, be turned inward, as shown in Figs. 7 and 8, so as to constitute a funnel by which any liquid expelled is conveyed back into the receptacle E before it leaves the casing B, or, as shown in Fig. 4, a part of double funnel K may be made to slide within the casing B, it normally being at the lower end thereof. The orifice at K between the upper and lower parts of the funnel is not large enough to allow the end of the receptacle E to pass through, but is large enough not to interfere with the closing of the said receptacle by the closing device a². When the receptacle E is inserted into the casing B, the funnel K is carried upward by the receptacle, and upon releasing the mouth of the receptacle from the closing device any liquid which may be expelled from the receptacle by the sudden ebullition of gas will be received by the funnel K, which, following the receptacle E in its withdrawal from the casing B, allows the liquid so received by the funnel K to run back into the receptacle E before the said receptacle has left the casing B.

I claim as my invention—

1. An aerated-liquid-dispensing apparatus, comprising a casing, a closing device and a charging device within the casing connected to a container and adapted to be operated by pressure against the closing device, a presser

and presser-lever adapted to press an intermediate vessel in the casing against the closing device to cause the vessel to be filled, substantially as described.

5. 2. An aerated-liquid-dispensing apparatus, comprising a casing, a closing device and a charging device within the casing connected to a container and adapted to be operated by pressure against the closing device, a presser and presser-lever adapted to press an intermediate vessel in the casing against the closing device to cause the vessel to be filled, substantially as described.

10 3. Apparatus for dispensing aerated liquid, comprising a casing open at one end, a pressure-operated charging device and a closing device within the closed end of the casing, and a presser-lever pivoted to the casing and adapted to press an intermediate vessel against the closing device to operate the charging device, substantially as described.

15 4. An aerated-liquid-dispensing apparatus,

comprising a casing, a closing device and a 25 charging device within the casing connected to a container and adapted to be operated by pressure against the closing device, a presser and presser-lever adapted to press an intermediate vessel in the casing against the closing device to cause the vessel to be filled, substantially as described.

30 5. An aerated-liquid-dispensing apparatus, 35 comprising a casing, a valve in the casing, a longitudinally-movable funnel in the casing adapted to convey excess expelled liquid to an intermediate vessel as it is withdrawn from the casing, said funnel being provided with 40 an opening to fit the mouth of the intermediate vessel, substantially as described.

In testimony whereof I affix my signature in presence of two witnesses.

WILLIAM HUCKS, JUNIOR.
